COPY MACHINE DEVELOPING APPARATUS
 Frederick G. Wilde, Rochester, N.Y., assignor to Addressograph-Multigraph Corporation, Charles Bruning Division, Mount Prospect, Ill., a corporation of Delaware
 Filed Sept. 21, 1964, Ser. No. 397,713
 3 Claims. (Cl. 95—89)

This invention relates to copy machines of the direct contact printing type and more particularly to new and improved apparatus for developing sensitized material in such machines.

Machines capable of quickly and economically making copies of an original are in constant demand for business establishments and the like. Of the various types of copy machines in use, the diazo, or direct contact type affords extremely accurate copies at low cost. In such a contact printing process, a photosensitive copy sheet is superimposed over the original and selectively exposed to light and the sensitized sheet is then developed in a developing chamber by exposure to a developing gas, such as ammonia. This invention relates to improvements in developing chambers.

Conventional copy machines of the direct contact type include a developing chamber in the form of a tank open at one side to form an area where sensitized material is developed by exposure to a developing gas. Guide rollers and driving means draw a copy sheet across the exposure area, and the tank is provided with a supply of ammonia and water vapor. Customarily, ammonia and water vapor is supplied by feeding a water solution of ammonia into an evaporating tray positioned in the tank where a heater near the tray vaporizes the liquid. Another variation used in the past is to feed water into the evaporating tray, and to supply anhydrous or dry ammonia to the tank through a suitable piping arrangement. One type of developing chamber is illustrated and described in my Patent No. 2,909,980, issued Oct. 27, 1959.

Improvements in copy machines and the use of super-fast diazo compounds has greatly reduced the time required to expose copy sheets. Thus it would be desirable to increase the speed of the developing process as well and it has been suggested that the developing speed be increased by increasing the size of the developing tank, however this solution is unsatisfactory due to the disadvantages of the large and expensive developing chamber that would be required. In fact, the inclusion of standard sized evaporating trays in conventional developing tanks makes them of an undesirably large size in view of the demand for compact copy machines.

Additional disadvantages of conventional developing chambers, in addition to their large size and their slowness, are that they must be used in a level position for proper functioning of the evaporating tray, and that they must be provided with metering valves and synchronization equipment to control the input of ammonia and water vapor.

Accordingly, it is an object of the invention to provide a developing chamber for sensitized material in which the above-mentioned disadvantages are overcome.

It is another object to provide a developing chamber for the extremely rapid developing of sensitized material.

It is a further object to provide a developing chamber of convenient small size.

It is another object to provide a developing chamber that does not require an evaporating tray or vaporizing heater, so that level installation is not required.

Briefly, an embodiment of the invention may comprise a developing tank open on a portion of its surface to form an exposure area for sensitized material drawn past the area by means of an endless sleeve which serves to seal

2

the tank. A series of spaced guide rollers or the like holds the sensitized material being developed against the endless sleeve. Inside the tank there is provided means for supplying ammonia or other developing gas, and although the customary evaporating tray may be used, in one embodiment of the invention anhydrous ammonia gas is piped directly into the tank. A perforated conduit is provided for supplying a stream of steam within the tank, and the conduit is arranged so that the steam is directed past the ammonia supply and impinges upon the sensitized material at the exposure area. Additionally, a heater may be provided adjacent the perforated conduit to superheat the steam.

Other objects and advantages and a better understanding of the invention will appear from the following detailed description in conjunction with the appended drawings in which:

FIG. 1 is a sectional fragmentary view of a copy machine embodying the present invention;

FIG. 2 is an enlarged sectional view of an alternative embodiment of a developing chamber in accordance with the invention;

FIG. 3 is a sectional view of the chamber of FIG. 2, taken along the line 3—3 of FIG. 2; and

FIG. 4 is an enlarged elevational view of the steam conduit of the machine of FIG. 1.

Having reference now to the drawings and particularly to FIG. 1 there is illustrated a copy machine 10 constructed in accordance with the present invention. The copy machine 10 is of the diazo or direct contact type and includes a feeding assembly 12 for supplying an original to be copied and a photosensitive copy sheet 13 to an exposing assembly 14, where they are superimposed and fed onto a transparent drum 16 having a suitable light source 18. After the copy sheet 13 has been exposed it is separated from the original and from the drum 16 and advanced to a developing assembly 20. As the invention relates to the novel developing assembly 20, and since a detailed description of the exposure and feeding apparatus of the copy machine 10 is available in U.S. patents of Sherell E. Campbell et al., Nos. 3,215,055 and 3,215,056, the remaining structure of the copy machine 10 will not be further described.

The developing apparatus 20 in accordance with the invention is adapted to develop the sensitized material associated with the exposed copy sheet 13 by exposure of the sensitized material to a developing medium, such as ammonia gas. To this end the developing apparatus 20 includes a tank 22 having an opening 24 at one side 50 thereof which serves as an exposure area and is closed by means of an endless belt 26 moving across the tank 22. When a copy sheet 13 is fed to the developing apparatus 20 it is engaged by the endless belt 26 and is carried across the exposure area 24. In order to supply ammonia within the tank 22 an ammonia input pipe 28 carries anhydrous or dry ammonia gas from a tank or other suitable source to the interior of the chamber 22.

In accordance with a novel feature of the invention a conduit 30 transports steam into the tank 22, and interconnects the tank 22 and a suitable source of steam at a pressure slightly above atmospheric pressure. As may clearly be seen in FIG. 4, the conduit 30 has perforations 32 along its length arranged so that the steam supplied by the conduit is directed in a spray or stream as indicated by the wavy lines 34. The steam travels past the supply of ammonia and impinges upon the sensitized copy sheet 13 as it is drawn into the exposure area 24. Perforations 32 may comprise a series of small openings as shown in FIG. 4, or alternatively, one or more elongated slots may be provided.

It has been found that the provision of steam in accordance with the invention greatly increases the effectiveness

of the ammonia gas developing process, greatly increasing the developing speed. Possible reasons for the increase of developing speed are first that the steam preconditions the sensitized material on the copy sheet 13 for rapid development by increasing its moisture content. Additionally, the stream of steam may envelop the photosensitive material in a narrow layer of water vapor. In view of the great affinity of ammonia to water, the flow of ammonia to the sensitized material would thereby be greatly accelerated. Another possibility is that the spray of steam traveling past the supply of ammonia entrains ammonia vapor and transports it efficiently to the sensitized material. Whether the increased effectiveness of the developing process results from one or more of the above explanations, or from other reasons, experimentation has indicated that the supply of steam provided in accordance with the invention greatly decreases the time required for development of the sensitized material.

The tank 22 associated with the developing apparatus 20 is formed of a gas impermeable material such as sheet metal or the like and includes a bottom wall 36 and side walls 38. The side walls 38 are rolled inwardly to form annular beads 40 defining the exposure area opening 24, and act as sealing lips cooperating with the endless belt 26 to seal the tank 22.

The endless belt 22 is made in conventional manner of rubber or other flexible material impervious to ammonia and other developing gas, and is driven at one end by a drive roller 42 mounted upon a driven shaft 44 and is supported at the other end by an idler roller 46 mounted upon an idler shaft 48. The belt 26 thus acts as an endless sealing sleeve in engagement with the annular beads 40, and is driven across the exposure area 24 in the direction indicated by arrows in FIG. 1. The belt 26 engages sensitized copy sheets 13 and transports them across the exposure area 24, its speed of travel being suitably regulated in any known manner to accomplish the developing process.

Within the tank 22 there is a series of rollers 50 for supporting the copy sheets 13 in engagement with the belt 26. The rollers 50 are mounted for rotation upon shafts 52, and each of the rollers is provided with perforations 54 which allow the developing gas to diffuse freely within the tank 22. The shafts 52 are mounted for rotation in suitable U-shaped brackets 56.

In connection with this first embodiment of the invention as illustrated in FIG. 1, the customary evaporation tray used in conventional developing apparatus has been eliminated and the size of the tank 22 is considerably smaller than has heretofore been possible. In view of the modern effort to provide more compact copy machines, the reduction in size made possible by the invention is highly desirable. In addition, elimination of the evaporation tray has rendered installation of the apparatus far less critical than for conventional developers since it is not necessary to level the tank 22 to assure proper fluid distribution.

Thus it can be seen that the embodiment of the invention illustrated in FIG. 1 is a great improvement over conventional developing apparatus, since it is smaller, operates faster, and does not require level installation. However, although this embodiment is useful for incorporation into new copy machines, it would be desirable to obtain some of the advantages of the invention in previously constructed machines without the expense of completely replacing the developing apparatus. To this end there is illustrated in FIGS. 2 and 3 another embodiment of the invention which represents a conventional developer converted to embody the invention.

The developing assembly of FIGS. 2 and 3, indicated generally by the numeral 58, includes a conventionally shaped developing tank 60, having side walls 62 rolled inwardly to form annular beads 64 and defining an exposure area opening 66. The tank 60 includes a large rear portion 68 formed of a bottom wall 70 and inclined wall

portions 72 and housing an evaporation tray 74 and a vaporization heater 76. The evaporation tray 74 is suspended from the tank 60 by means of brackets 78, and is supplied with a liquid mixture of water and ammonia which is evaporated in the usual fashion by the heater 76 to supply developing gas while a space heating element 80 heats the space within the tank. The assembly 58 also includes an endless belt 82 and a pair of perforated guide rollers 84, mounted on shafts 86 journaled in U-shaped supports 88.

In accordance with the invention the conventional developing assembly 58 may be adapted for high speed operation through the provision of a steam conduit 90 having perforations 92 (FIG. 2) along its length. The perforated conduit 90 leads from a suitable source of steam at a pressure slightly above atmospheric pressure, and is arranged to direct a stream or spray of steam, as indicated by the way lines 94, over the evaporation tray 74 and against the copy sheet 13 in the exposure area 66.

In order to allow the steam introduced into the tank 60 by the conduit 90 to travel freely to the sensitized material, a flexible resilient guide 96 (FIG. 3) may be used in place of one of the guide rollers 84 used in conventional developers. The guide 96 may be constructed of any resilient material which is unaffected by the developing gas and serves to hold the copy sheet 13 against the endless belt 82.

In accordance with another feature of the invention, and as illustrated in FIGS. 2 and 3, a heating element 98 extends parallel with the conduit 90 along its length within the tank 60 and serves to superheat the steam carried by the conduit into the tank. It has been found that this superheating operation increases the developing speed, and it should be appreciated that, if desired, a superheating heater might also be used with the conduit 30 of the embodiment of the invention illustrated in FIGS. 1 and 4.

Although the embodiment of the invention illustrated in FIGS. 2 and 3 does not have the advantage of small size, as does the embodiment illustrated in FIG. 1, nevertheless the embodiment of FIGS. 2 and 3 is highly useful since it is of prime importance to make existing machines, having slow developing apparatus, suitable for higher speed operation. The provision of the perforated conduit 90 in the conventional developer 58 enables the developing speed to be greatly increased. For example, in a device constructed in accordance with the invention the developing speed was increased from 75 feet per minute to 128 feet per minute.

It has been found that the perforated steam conduit of either embodiment may be placed outside of the developing tank in a position to direct a spray of steam onto the copy sheets 13 just before they enter the developing tank. When this is done, a significant increase in developing speed is realized over conventional developers which do not use a spray of steam. It is believed that this result is due to a pre-conditioning of the moisture content of the sensitized material to be developed.

In devices constructed in accordance with the invention, it was not necessary to provide metering valves and synchronization equipment for controlling the flow of materials to the developing chamber. In addition, the control of moisture conditions within the tank for different types of sensitized material may be accomplished in a simple manner by regulating the flow of steam.

Although the present invention has been described with reference to specific illustrative embodiments thereof, it should be understood that numerous other modifications and embodiments can be devised by those skilled in the art that will fall within the spirit and scope of the invention.

What is claimed as new and desired to be secured by Letters Patent of the United States is:

1. Apparatus for developing light sensitized material exposed in a direct contact printing process having a

latent image on one surface thereof, comprising: a tank having an exposure area, an endless belt driven across said exposure area for sealing said tank and for drawing said sensitized material across said exposure area, a series of spaced guide means within said tank for holding said material against said belt with the image bearing surface facing away from said belt, means within said tank for supplying developing gas to said exposure area and including a developing gas supply conduit arranged adjacent the exposure area terminating within said tank, a perforated second conduit within said tank for supplying a stream of steam at a pressure slightly above atmospheric pressure, said second conduit being in a position immediately adjacent the image bearing surface entering the exposure area to direct steam past said developing gas conduit and past said guide means forcibly impinging said image bearing surface simultaneously with exposure to said developer gas.

2. The apparatus set forth in claim 1, wherein the developing gas is in the form of anhydrous gas.

3. The apparatus of claim 1 additionally comprising a heater adjacent said perforated second conduit for superheating said steam.
